United States Patent Office

Des. 191,897
Patented Dec. 5, 1961

191,897

COMBINED AQUARIUM AND SUPPORT THEREFOR

Richard Shirley, 5234 Spicer St., Toledo, Ohio

Filed May 3, 1961, Ser. No. 65,013

Term of patent 14 years

(Cl. D91—2)

FIGURE 2.

FIG. 1 is a view in front perspective of a combined aquarium and support therefor showing my new design; and

FIG. 2 is a side elevation thereof on a reduced scale.
I claim:

The ornamental design for a combined aquarium and support therefor, substantially as shown.
